FIG. 7

FIG. 1 is a perspective view of a barbecue grill showing my design.

FIG. 2 is a front elevation of the barbecue grill shown in FIG. 1.

FIG. 3 is a fragmentary rear elevation of the barbecue grill shown in FIG. 1.

FIG. 4 is a left side elevation of the barbecue grill shown in FIG. 1, with the removable cover detached.

FIG. 5 is a right side elevation of the barbecue grill shown in FIG. 1, with the removable cover in a closed position.

FIG. 6 is a bottom plan view of the barbecue grill shown in FIG. 1. The top of the casing portion is substantially the same in appearance as the bottom except for the operating lever and slots.

FIG. 7 is an enlarged fragmentary perspective view of a central portion of the inside bottom of the barbecue grill as shown in FIG. 1.

I claim:

The ornamental design for a barbecue grill, substantially as shown and described.
